UNITED STATES PATENT OFFICE.

LUTHER NELSON WHITE, OF COLUMBIA CITY, ASSIGNOR OF ONE-HALF TO
WILLIAM W. WORTHINGTON AND ROBERT C. BELL, OF FORT WAYNE,
INDIANA.

NUT-LOCK.

SPECIFICATION forming part of Letters Patent No. 326,075, dated September 8, 1885.

Application filed April 30, 1885. (No model.)

To all whom it may concern:

Be it known that I, LUTHER N. WHITE, a citizen of the United States, and resident of Columbia City, in the county of Whitley and State of Indiana, have invented certain new and useful Improvements in Nut-Locks; and I do hereby declare that the following is a full, clear, and exact description of the invention, which will enable others skilled in the art to which it appertains to make and use the same, reference being had to the accompanying drawings, which form a part of this specification, and in which—

Figure 1 is a view showing in perspective the several parts of my improved nut-lock separated or detached from each other. Fig. 2 is a longitudinal vertical sectional view of the nut-lock complete. Fig. 3 is a transverse sectional view of the nut, taken through one of the recesses in the same, with the corrugated roller in position. Fig. 4 is a view illustrating means for keeping the rolls in position in the nut previous to the adjustment of the latter upon the bolt. Fig. 5 is a sectional view of one of the rolls, illustrating a modification in the construction of the same; and Fig. 6 is a perspective view illustrating a modification in the construction of the washer.

The same letters refer to the same parts in all the figures.

This invention relates to nut-locks, and it has for its object to provide a device of this class which shall possess superior advantages in point of simplicity, durability, and general efficiency.

With these ends in view, the invention consists in the improved construction, arrangement, and combination of parts, which will be hereinafter fully described, and particularly pointed out in the claims.

In the drawings hereto annexed, A designates a bolt of ordinary construction, which is to be inserted in the usual manner through the openings or perforations in the parts which are to be connected, and upon the end of which is placed a washer, B.

C is a nut, the inner face of which is provided, on opposite sides of the hole D, with parallel beveled grooves or recesses E E, the bottoms of which are beveled in opposite di-

rections, as shown, and in which are seated the cylindrical rolls F, the peripheries of which are corrugated or provided with ratchet-teeth G, which, when the said rolls are at the lower ends of their respective recesses, shall barely project beyond the face H of the nut.

The operation of this invention will be readily understood. When the nut is tightened up against the washer, the serrated rolls will be driven to the lower ends of their respective recesses, and the teeth of the said rolls will barely bite in the face of the washer. When the nut has been thoroughly tightened so as to effect this result, any movement of the nut in a reverse direction will cause the rolls to travel toward the upper ends of their respective recesses, thereby tightening or straining the nut and washer in opposite directions upon the bolt, and absolutely preventing not only the nut from working loose, but its removal by any means except by breaking the parts.

When it shall be desired to so arrange the nut that it may be removed when occasion demands without breaking the bolt, I avail myself of the modification in the construction of the rolls shown in Fig. 5 of the drawings. The said rolls are in this case made hollow or tubular, so that by the application of proper force they may be crushed, thus enabling the nut to be removed.

In order to enable the nut to be easily manipulated and adjusted without the rolls dropping out, as they would be liable to do until the nut and washer have been brought sufficiently close together, I propose to moisten the face of the nut by mucilage or adhesive material of any kind, and apply thereto a thin sheet of soft paper, as shown at J in Fig. 4, covering the rolls and serving to keep them in their respective recesses. When the nut is tightened up against the washer, this paper will easily break and leave the serrated edges of the rolls exposed for action.

When the device is to be applied to wood-work, the inner face of the washer B may be provided with ribs K, adapted to enter the wood, and keep it from turning upon the bolt. A washer thus constructed has been shown in Fig. 6 of the drawings.

From the foregoing description, taken in connection with the drawings hereto annexed, the operation and advantages of this invention will be readily understood.

5 The construction is simple and inexpensive, and the device is easily adjusted, and effective in operation.

Having thus described my invention, I claim and desire to secure by Letters Patent of the

10 United States—

1. In a nut-lock, the combination of a bolt, a washer, a nut provided on opposite sides of its hole with beveled parallel recesses in its inner face, and serrated or ratchet-toothed rollers seated in said recesses, the dimensions 15 being such that when the said rolls are at the bottoms of their respective recesses their

teeth shall project beyond the inner face of the nut, substantially as and for the purpose set forth.

2. In a nut-lock, the combination, with the nut having the beveled recesses in its inner face, of the hollow or tubular serrated or ratchet-toothed rolls seated in the said recesses, substantially as and for the purpose set 25 forth.

In testimony that I claim the foregoing as my own I have hereunto affixed my signature in presence of two witnesses.

LUTHER NELSON WHITE.
